UNITED STATES PATENT OFFICE.

PETER DELICH, OF NOPEMING, MINNESOTA.

CUP.

Application filed November 12, 1923. Serial No. 674,393.

To all whom it may concern:

Be it known that I, PETER DELICH, a subject of the King of Serbia, residing at Nopeming, in the county of St. Louis and State of Minnesota, have invented certain new and useful Improvements in Cups, of which the following is a specification, reference being had therein to the accompanying drawing.

10 This invention relates to receptacles and has special reference to a novel form of knocked down receptacle particularly designed for use as a cup, either for drinking purposes, egg cup, or the like; it being 15 preferably of a form representative of an egg.

The principal object of the invention is to provide a convenient form of knocked down cup, which may be easily and safely 20 transported from place to place, and used for a number of purposes.

Other objects and advantages of the invention will appear in the further description thereof.

25 Referring to the accompanying drawing forming part of this application, and in which like reference characters indicate like parts:

Figure 1 is a side elevation of the 30 proved receptacle as knocked down and assembled for transportation;

Figure 2 is a vertical transverse sectional view of Figure 1, showing the relative positions of the various parts; and

35 Figure 3 is a side elevation of the device assembled as a drinking or egg cup.

The major portion of the receptacle comprises the body 1, and cap or cover 2, the latter being provided with an externally 40 screw threaded stepped edge 3, which is screw threadedly mounted within the upper open end of the body portion 1, and, when thus united, resembles the general form of a large egg.

45 The lower end of the body portion 1 is preferably increased in thickness and provided with an internally screw threaded hole into which may be screwed, either from the interior or the exterior of the body 50 portion, the shank 4 of the pedestal or support 5 of the cup.

When the pedestal 5 is attached from the interior of the cup it will appear as shown

in Figure 2, forming a compact and neat assemblage for transportation, the pedestal 55 of course being no larger than the interior of the body portion. When, however, the pedestal is attached as shown in Figure 3, it is apparent that a very conveniently shaped goblet-like cup is formed which may 60 be used either for ordinary drinking purposes or as an egg cup, as previously described.

The base of the pedestal 1 is of general spherical form, preferably with openings 65 therethrough, particularly for appearance sake, and transverse the central portion thereof, is a web 7, the object of which is to provide means for finger and thumb manipulation of the pedestal in screwing it 70 either to or from the body portion of the receptacle.

From the foregoing it is apparent that I have devised an exceedingly simple and attractive form of knocked down receptacle 75 and one of such shape as to permit of the maximum amount of use, without breakage when knocked down, and one pleasing in appearance when assembled, it being evident that the same may be constructed of any 80 kind of material desired, such, for example as aluminum, silver, gold, or glass.

Having thus described my invention, what I claim and desire to secure by Letters Patent, is:

85 A receptacle of the type described comprising a principal body portion and a separable cap therefor, said cap and body portion when united being substantially egg shaped and hollow, a pedestal for said body portion screw threadedly unitable to the lower end thereof either externally or internally, the hollow base of said pedestal being somewhat similar in shape to the interior of the body portion and snugly fitting 90 therein below the line of separation between the body portion and the cap, and a diametrically disposed web transverse the hollow base portion and formed integral therewith for the purpose described. 100

In testimony whereof I hereunto affix my signature in the presence of two witnesses:

PETER DELICH.

Witnesses:

S. GEO. STEVENS,
S. C. BRONSON.
